(57) **CLAIM**

The ornamental design for a tablet computer holding fixture, as shown and described.

DESCRIPTION

FIG. 1 is a front, top, perspective view of a tablet computer holding fixture, illustrating the novel design.

FIG. 2 is an exploded view of the front, top, perspective view thereof.

FIG. 3 is a top view thereof.

FIG. 4 is a bottom view thereof.

FIG. 5 is a front view thereof.

FIG. 6 is a rear view thereof.

FIG. 7 is a right side view thereof; and,

FIG. 8 is a left side view thereof.

The broken lines, if any, in the drawings depict unclaimed subject matter only and form no part of the claimed design.

1 Claim, 8 Drawing Sheets
